UNITED STATES PATENT OFFICE.

ALVAH M. GRIFFIN, OF KANSAS CITY, MISSOURI.

AIR-BLAST OIL-STOVE.

1,279,536.

Specification of Letters Patent. Patented Sept. 24, 1918.

Application filed November 12, 1917. Serial No. 201,854.

To all whom it may concern:

Be it known that I, ALVAH M. GRIFFIN, a citizen of the United States, residing at Kansas City, in the county of Jackson and 5 State of Missouri, have invented certain new and useful Improvements in Air-Blast Oil-Stoves, of which the following is a specification.

This invention relates to oil stoves of that 10 class in which the flame from the wick is subjected to a blast of air and instantly transformed into a blue flame generating intense heat, and which is characterized by the use of a blast of air from below the top of the 15 wick as distinguished from natural draft or suctional action, so that the flame can be caused to impinge directly on the bottom of a cooking vessel, or onto a refractory mantle if illumination is desired.

20 The object of the invention is to produce a burner adapted for generating intense heat, particularly for cooking purposes, with a liquid as the fuel, a wick for conducting the fuel to the ignition point, and a guided 25 air blast for vaporizing the fuel at the ignition point and supplying oxygen thereto in sufficient volume to produce a blue flame for impingement directly against the bottom of a cooking utensil or the like.

30 With these objects in view the invention consists in certain novel and useful features of construction and combinations of parts as hereinafter described and claimed; and in order that it may be fully understood reference is to be had to the accompanying 35 drawing, in which:—

Figure 1, is a vertical section of an oil stove embodying the invention.

Fig. 2, is horizontal section on the line 40 II—II of Fig. 1.

Fig. 3, shows the burner associated with a mantle for illuminating purposes.

In the said drawing, 1 indicates a hollow conduit for air, and which in Figs. 1 and 45 2, is in duplicate and within a stove body 2, and in Fig. 3, is in the form of a pipe leading from any suitable point where it will be convenient to locate a blast producing device, such as an electrically-driven fan shown in 50 Figs. 1 and 2, and hereinafter identified.

In the top of the stove body are openings 3 with which the upper ends of the conduits register, and within the upper ends of the conduits are tubular wick tubes 4, 55 containing wicks 5, and the customary wick-adjusting devices, not shown because of com-

mon and well-known construction and operation. The wick tubes are equipped with overhanging flame spreaders 6, and depending from the said spreaders within the wick tubes are inverted conical air-deflectors 7, supported from the tubes by braces 8. The tubes are spaced from the respective conduits so that air may pass up around the tubes as well as through the central passages 65 thereof, the air passing up through said passages being directed outward over the walls of the tubes and the wicks thereof. This air is intercepted by the air passing upward externally of the tubes, and at the upper ends of the conduits are inwardly-tapering walls 9, to intercept the outwardly traveling flame to direct it upward. A fan 10, shown only in Figs. 1 and 2, creates a blast of air up through the conduits, 75 and to regulate or control the force of the blast each conduit is provided with a valve or damper 11. In Figs. 1 and 2, the fan is shown in the stove body and discharges air directly therein and it then passes up 80 through the conduits of which the chamber of the stove forms a part, and to give access to the fan and admit air thereto, an opening 12 is formed in a wall of the stove and is closed by a screen door 13 to exclude 85 floating particles.

Any suitable means may be employed to operate the motor, the preferred construction being an electric fan connected by wires 14, to a storage battery 15 of suitable voltage 90 and amperage.

The preferred method of operating the burner is to apply a lighted match to the wick in the usual manner, and then instantly turn on the switch 16, controlling the flow 95 of current from the battery. This current starts the fan and a blast of air is instantly created and discharged over and around the wick as explained. If the flame is too high it can be cut down by lowering the wick, 100 the flame under the blast being blue and developing intense heat. The volume of flame can be also regulated by the adjustment of the valves or dampers, the latter being perhaps more desirable on an illuminating burner than on a stove burner because of the fragility of the refractory mantle 17, used with the burner when used for illuminating purposes.

When the burner is started it instantly 110 develops great heat and the flame will remain constant without readjustments of the

wick, and because of the fact that the air blast comes from below the top of the wick, there is no loss of efficiency by radiation of heat, as the flame impinges directly on the 5 bottom of the vessel as on a gas range.

I claim:

1. In an oil burner a flame opening, an air conduit communicating at its upper end with said opening and of contracting diameter at such end, a tubular receptacle for a wick and liquid fuel fitting concentrically in said conduit at the upper end thereof, the upper end of said receptacle and wick occupying the same horizontal plane as the 15 contracting end of the air conduit; said tubular receptacle in conjunction with the enclosing conduit providing an air passage exterior to the wick, and an inverted conical spreader depending centrally within the 20 passage of the wick receptacle for deflecting air from said passage, upwardly and outwardly against flame from the wick, the spreader also overlying the wick and in conjunction with said conduit, reducing the

opening in the top of the stove to a narrow 25 slit for the emergence of the flame, and means for supplying air under pressure, to the lower end of said conduit.

2. The combination of a stove provided with a chamber, an air conduct communicating at its upper end with an opening at the top of the stove and below said end with said chamber, a tubular receptacle for a wick and liquid fuel, inclosed by said conduit at the upper end thereof, said receptacle fitting loosely in the conduit to provide an interposed air passage, a conical spreader depending within the passage of said wick tube and also overhanging the wick thereof, a screen covered opening in 40 the wall of said stove chamber, a suitably driven fan for conducting external air through said screened opening into said chamber at suitable pressure, and a damper for regulating the supply of air accessible 45 to said conduit from said chamber.

In testimony whereof I affix my signature.

ALVAH M. GRIFFIN.
